UNITED STATES PATENT OFFICE

165,318

HOUSING FOR KNIFE SHARPENERS

Alfred E. Anheuser, West Allis, Wis.

Application November 1, 1950, Serial No. 12,811

Term of patent 14 years

(Cl. D37—1)

To all whom it may concern:

Be it known that I, Alfred E. Anheuser, a citizen of the United States, residing at West Allis, in the county of Milwaukee and State of Wisconsin, have invented a new, original, and ornamental Design for a Housing for Knife Sharpeners, of which the following is a specification, reference being had to the accompanying drawing, forming part thereof.

Figure 1 is a perspective view showing the top, front and one end of a housing for knife sharpeners embodying my new design;

Figure 2 is a top plan view of the housing shown in Figure 1;

Figure 3 is a rear elevational view of the housing shown in Figure 1; and

Figure 4 is an elevational view of the housing looking at the end thereof opposite that seen in Figure 1.

I claim:

The ornamental design for a housing for knife sharpeners, as shown.

ALFRED E. ANHEUSER.
